UNITED STATES PATENT OFFICE.

ELMER P. NICHOLS, OF MANCHESTER, NEW HAMPSHIRE, ASSIGNOR TO LACENE MANUFACTURING COMPANY, OF MANCHESTER, NEW HAMPSHIRE, A CORPORATION OF MAINE.

LEATHER-GRADING MACHINE.

1,113,472.

Specification of Letters Patent.

Patented Oct. 13, 1914.

Application filed July 9, 1906. Serial No. 325,224.

To all whom it may concern:

Be it known that I, ELMER P. NICHOLS, a citizen of United States, residing at Manchester, in the county of Hillsboro and State of New Hampshire, have invented an Improvement in Leather-Grading Machines, of which the following description, in connection with the accompanying drawings, is a specification, like letters on the drawings representing like parts.

My present invention is a simplified form of leather-grading and marking machine, being an improvement on the invention set forth in my foundation patent Reissue No. 12,288 dated Nov. 22, 1904. In my said patent I provide feeding mechanism which carries the leather piece beneath a feeler which travels over the leather piece and transmits its varying determinations to a gaging mechanism and the latter is automatically locked at the proper time and then the measurement thus found is transmitted to a grading or marking mechanism which marks the leather piece as the latter is fed beneath it. This measures a thin spot. In a subsequent application now Patent No. 841,809 dated Jan. 22, 1907, I have set forth means for determining the thinnest spot in a given area. My present invention determines and marks the thinnest spot in the piece, or in any given area or portion of the piece, and accomplishes the result by very different and much more simple mechanism than before. There is no feeding mechanism, the entire given area is all felt of simultaneously, there is solely a pressing or a vertical engagement of the leather and hence no rubbing or thinning-down movement over the leather, the feelers engage according to a predetermined pattern or contour, the machine is manually controlled, the dial or marker is positively and directly locked and unlocked, so that it is exactly accurate, cannot slip, etc., and there are various other features of simplicity, durability and accuracy, which, together with a further explanation of the leading advantages, will be set forth in the following description.

In the accompanying drawings I have shown a preferred form of my invention, specially adapted to died-out leather, such

as soles, taps, top-lifts, counters, and the like.

In the drawings, Figure 1 is a central vertical sectional view through the machine; Fig. 2 shows the operating mechanism in side elevation, parts being broken away and sectioned to exhibit more clearly said operating mechanism; Fig. 3 shows in top plan the vertical slide and adjacent parts, the adjacent uprights 1, 2 being sectioned; Fig. 4 shows in vertical section, taken centrally of the driving shaft, the adjacent parts; Fig. 5 is a top plan view of the 65 feelers and adjacent parts; Fig. 6 is a fragmentary view of one of the feelers and the adjacent parts, portions thereof being broken away and sectioned to exhibit the internal construction. 70

It is frequently desirable to furnish cut soles, taps or half-soles, etc., to the trade, simply graded, without being evened. This enables the shoe-manufacturer to exercise his own judgment as to whether he will even 75 closely and accurately or not. Hence the supply house does not need the evening mechanism of my previous machine, and I have accordingly invented a much simplified and more economical machine, specially 80 designed for such uses, a machine, moreover, which is extremely accurate and reliable, not liable to get out of order, and so constructed that it cannot be interfered with or become clogged with dust, or the 85 like.

The leading features of my present invention may be embodied in a wide variety of mechanical details, one of the preferred mechanism being herein set forth. Between 90 suitable uprights 1, 2, of the frame are carrier plates 3, 4, separated to provide a pocket or holder opening 5 for a templet or pattern 6. These carrier plates are provided with a series of radiating slots or 95 guideways 7 in which are slidably mounted feeler carriers 8, consisting of upper and lower hubs 9, 10, whose laterally extended flat ends maintain certainty of position, being connected by hollow necks 11 in which 100 are longitudinally movable feeler pins or detectors 12 normally held upwardly as shown by heavy springs 13 for flattening out the leather piece and maintaining their

blunt top ends 14 in unremitting engagement with the under side of the flattened leather piece 15, being graded as will presently be explained, said feeler carriers 8 5 also carrying guards or position controllers 16, yieldingly supported on springs 17. These carriers 8 are held yieldingly toward each other by any suitable means, as springs 18, 19, and have loose connection with a 10 gaging lever 20 by means of a steel link 21 and a lever 22 and horizontal head 23, slotted to correspond to the carrier plates, said head having its depending stem 23' held in a long bearing 24 and adapted to be raised 15 by the engagement therewith of any one or more of the adjusting nuts or flanged ends 25 of the upwardly impelled feelers 12.

The gaging lever is normally retracted by a spring 26, acting in opposition to the 20 springs 18 to take up all wear and prevent lost motion, and to insure accuracy of movement, and at its upper end 27 is adjustably connected at 28 to a long arm 29 provided with a fine rack 30 engaging a pinion 31 of 25 the grade indicator. Said arm 29, together with the rack and pinion, constitute controlling means for the indicator which serves as the preferred means for classifying the stock; and the mechanism back to, and including, the feelers or detectors 12 constitutes means for setting or adjusting said controlling means and, thereby, said indicator. The machine of the drawings indicates the grade by actually stamping or 35 marking it on the leather pieces, and is of the wheel type. The pinion 31 is fast on a die or marking wheel 32 journaled at its opposite ends in a slide 33 (shown as consisting of two parallel parts rigidly connect- 40 ed to retain between them said wheel) moving in ways 34 of a carrier frame or actuator 35, operating vertically between the upper ends of the uprights 1, 2, and provided at its lower end with a blank flattener or stock- 45 engaging pressure-plate 36. The actuator 35 is vertically guided so as to move the stock-engaging plate 36 to approach the detectors or feelers 12 truly parallel thereto until said plate meets the leather piece, and then the 50 actuator 35 continues on downward, thereby actuating the feelers or detectors 12, in opposition to their springs 13 with an increasing pressure and as required in accordance with the thickness of the leather piece. The plate 55 36 bears down upon the top of the leather piece placed on the feelers or detectors 12 and thereby actuates the latter to set the grading wheel 32. The carrier frame 35 is held upwardly by springs 37 and is actu- 60 ated manually or by power by any suitable means, being preferably operated continuously by a shaft 38, driven by a belt pulley 39 and provided with cam surfaces 40, 41, 42 for respectively operating the carrier frame 35, 65 slide 33 and a locking detent 43 which is

normally moved by a spring 44 in opposition to the cam surface 42 to engage radial depressions 45 on the grade indicator wheel 32, thereby positively locking said wheel when set by the rack 30, etc. Steel wear plates 46, 70 47, are mounted in dove-tail grooves, see Fig. 1, in the carrier frame 35 and slide 33 to engage the cam surfaces 40, 41, and a clutch 48 operated by a foot lever, not shown, is provided for starting or stopping the machine as desired. The work is fed to the feelers beneath the pressure plate 36 which is cut away obliquely at 49 to enable the operator to read the mark on the leather as he is withdrawing it. 80

The manner of using my machine is exceedingly simple. Let it be supposed that soles are to be graded. These come from the cutting room in bunches arranged by sizes. The operator selects a pattern corresponding to the given size of soles to be graded, and inserts it in the opening 5 of the pattern holder. The pattern presses against the necks 11 of the feeler carriers 8, thereby separating the feelers 12 to correspond exactly 85 to the outline or perimeter of the soles to be graded. For ordinary purposes of taps and soles five feelers arranged as shown to engage the critical points of the edges of a sole 90 will detect the thinnest spot in that portion 95 of the sole with reference to which the sole must be graded, but the number and arrangement of feelers will be varied to suit the kind and character of the work. Having thus spaced and set the feelers in the predetermined arrangement, all that remains necessary to do is to start the machine and rest one sole after another on top of the feelers 12, the guards or position controllers 16 automatically guiding the blanks into correct position so as to bring their edges over the ends of the feelers. As the shaft 38 turns, it causes the cam 40, operating through frame 35, to depress the presser plate 36 into engagement with the sole which is immediately flattened out by the powerful combined pressures of all the feeler springs 13. The feelers at the same time are all held up by their respective springs 13 hard against the sole edge and hence operate simultaneously 110 to determine the relative thickness and thinness of the sole-edge over the desired region the head 23 being held up or positioned and controlled by that feeler which is depressed the least by the sole, i. e., by that feeler 115 which happens to engage the sole at the thinnest point to be detected, the other feelers being meanwhile moved by the thicker portions of the sole down slightly away from said head 23, with the result that the particular feeler, whichever it may be, that engages or detects the thinnest spot thereby determines the height or movement of the head 23, and although this movement is exceedingly slight it is amplified by the short-and- 120 125 130

long-lever arrangement of parts 22, 21, 20, 29, 30, 31, to rotate the grade indicator 32 to the precise distance required to bring the correct mark into marking position. Thereupon the cam 42 releases the detent 43 which is caused by spring 44 to interlock with the adjacent recess or notch 45 of the grade indicator or marking wheel 32, thereby locking the grade indicator in this position, and then 19 the cam 41 engages the slide 33 which quickly lowers the marking wheel into stamping contact with the leather. This marks the measured grade upon the sole. The rack lever 29 is so long and is so nearly 15 horizontal at the moment of marking that the slight vertical movement due to the cam 41 cannot affect the rotary position or accuracy of the marking wheel. The user can vary the marking to full or scant, by the 20 adjustment at 28. The parts of the machine are so arranged and are constructed to have so little movement that it is feasible to inclose the entire mechanism as indicated at 1, 2, and 50.

25 From the foregoing description it will be seen that my present invention reduces not only the mechanism but the operation to an exceedingly simple minimum. After setting the feelers, (which constitute the leather-engaging detecting means) he simply pushes the unmarked sole beneath the table or plate 36 and pulls it back graded and marked. He does not even have to let go of it, and, observing the mark as he 30 withdraws the work, he at once throws it into its proper rack. The cam movement controlling the presser plate 36 is so timed that the latter remains up and stationary during over half of the revolution, thereby 35 giving ample time for inserting and removing the soles, and hence permitting the machine to run continuously. I have so arranged the locking mechanism that the locking dog or pawl operates directly on the 40 grade indicator, so that there is no possibility of slip, lost motion or other inaccuracy.

45 Perhaps the most important improvement as to certainty and positiveness of measuring action, is the arrangement whereby the feeler movement is compelled to be certain and definite, due to the fact that the presser plate is simply lowered and the feeler pins are thereby simply pressed downwardly, 50 there being no following movement dependent upon the springs or the like for aiding the feeling as in my previous constructions. In the present construction the plate 36 is unyieldingly forced straight 55 down upon the leather piece, which in turn unyieldingly forces the feelers 12 straight down, the only variation in the downward movement of the different feelers being due to the variations in thickness of the leather. 60 The result is that the thickness (or thin-

ness) of the determinations must be accurate. The fact that there is no traveling detecting movement also aids in securing this same object of accuracy of determining the thin spots. In my previous mechanisms 70 the feeler or feelers were required to slide or roll over the leather, being raised or moved away by the thick places and caused to fall into thin places by the action of controlling springs, so that if a feeler should 75 stick the work would be inaccurate, or if the work passed more rapidly than the spring action could compensate for, the work would also be inaccurate. Instead of having the feelers pass over and respond 80 each to a plurality of spots in the leather piece, I provide a plurality of feelers each responding to one spot only in the leather piece, and instead of selecting that movement of one feeler which corresponds to 85 the thinnest of the plurality of spots detected by said one feeler, I provide mechanism for selecting and transmitting the movement of the one feeler, among the many feelers, which happens to engage and detect the 90 thinnest spot of the plurality of thin spots detected individually by the individual feelers.

95 Bearing in mind that leather is all bought by the pound, and that even a single pair of men's large soles will weigh fully a pound, and, if a fine grade, will average forty cents in value, it will be apparent that the success from a practical standpoint of a machine of this character depends upon 100 its absolute accuracy, as a variation of a quarter iron for instance (i. e., 1/192 of an inch) would make a difference of 100 pounds or \$40 in a day's work of eight thousand pairs of soles. Hence it has been my endeavor in the present machine to eliminate 105 all sources of possible inaccuracy in my previous mechanism. To the same end I have devised an arrangement which permits the use of a very large die or marking 110 wheel, so that the numbers or grade marks thereon can be spaced sufficiently apart to prevent any possibility of confusion, and also so that there is a maximum amplitude of movement for each grade indicated. The 115 presser plate 36 is positively depressed by the cam 40 upon the leather, which is flattened out and caused to positively press down the feelers, the rack 30 and pinion 31 positively turn the die wheel in its adjustment, and then the cams 40, and 42 positively hold all of said parts in unchangeable position while the cam 41 quickly depresses the stamp or marking die or wheel 120 to designate the grade upon the leather. 125

130 The marking, it will be observed, is done on the forepart as distinguished from the heelpart and hence the marking is done with ink, as an indented mark would injure the sole, applied at this point (said inking por-

tion of the machine being omitted inasmuch as any ordinary ink-applying device may be used). For this reason also, it is unnecessary to support the sole directly beneath the marking wheel, the supporting thereof at the edges by the series of feelers being sufficient.

In many respects, as will be evident from the claims, I consider my present invention as broadly new, and accordingly capable of a wide variety of mechanical embodiments without departing from the spirit and scope of the invention, although subordinate to my two patents before mentioned.

15 By the term "grading means" I mean any means for designating, as by marking, or any other way of differentiating or classifying, the different grades of stock, as fully explained in my before mentioned Patent 20 No. 841,809. Certain of the claims are more specifically limited to particular grading means, under the term "grade-indicating" means, by which is meant means serving to classify the leather either directly or indirectly by engagement with the leather or in some way bringing in a distinguishing element in connection with the leather piece, whereby the result of the leather-engaging detecting means is indicated to the operator 30 or is otherwise made available.

I do not herein claim the provision of power-actuated stock grading mechanism to grade the leather piece with reference to the thinnest spot detected by the feeler mechanism, combined with gaging or setting mechanism operating independently of the power mechanism to adjust said grading mechanism in accordance with the feeler mechanism, nor certain other features herein shown 40 but claimed broadly in my co-pending application Ser. No. 219,755 filed Aug. 6, 1904. Nor do I claim herein the generic provision of edge detecting means, broadly, located and restricted to operate with reference to 45 the rim or periphery of the died-out stock for detecting the thinnest of the plurality of thin spots felt of around the edge of said stock, nor the provision of feeler mechanism located to engage the leather piece on its 50 under side, nor, broadly, the provision, in connection with the aforesaid arrangement of feeler mechanism, of upwardly pressing spring counterbalancing means, as the generic claims to both of these features are 55 contained (in connection with a different species of these features of invention) in my co-pending application, Ser. No. 418,008, filed February 27, 1908; where also are the generic claims for the means for co-operating 60 with the feeler mechanism for increasing the pressure of the latter on the stock after the stock is first engaged thereby; and in my application Serial No. 507,728, filed July 13, 1909, I have claimed (in connection with 65 a different species) that feature of my pres-

ent invention relating to providing means adjacent the plurality of feeler posts and independent of the grading means for causing the stock to be gripped with an increased pressure from said posts after the stock is 70 first engaged.

Having described my invention, what I claim as new and desire to secure by Letters Patent is,

1. In a machine of the kind described, a 75 grade marker for shoe soles, taps, and the like, combined with leather-engaging detecting means constructed and operating to detect by vertical pressure only, a thin spot in the leather, means to maintain said detecting means, and the leather, at their point of mutual engagement, relatively stationary during the detecting operation, connecting mechanism, including means actuated by said detecting means, to set said grade 80 marker, means to lock the latter as set, and means to operate the marker to mark the leather piece, substantially as described.

2. In a machine of the kind described, a 85 grade marker for shoe soles, taps, and the like, combined with leather-engaging detecting means constructed and operating to detect and select by vertical engagement, pressure and movement only, with relation to the leather, the thinnest spot among a plurality 90 of edge spots engaged and detected in said leather, means for holding the leather stationary with relation to the engaging portions of said detecting means which engages the leather, while said edge-spots are 95 being detected, connecting mechanism, including means actuated by said detecting means to set said grade marker, and separate and independent means to operate said grade marker to mark on the leather the detected grade, substantially as described.

3. In a machine of the kind described, 100 grading means for shoe soles, taps, and the like, combined with means to detect the thinnest spot in a plurality of spots of different thicknesses in a predetermined area, said latter means including mechanism operating simultaneously at said plurality of spots, means for holding the leather stationary with relation to the portion of said detecting means which engages the leather, during the detecting operation, and connections from said detecting means for setting said grading means in accordance with the said thinnest spot, and means for operating said grading means as thus set, substantially as described.

4. In a machine of the kind described, 110 detecting mechanism responsive to the varying thicknesses throughout a considerable portion of the length of a leather piece, grading means, means controlled by the detecting mechanism and constructed and arranged to respond to the thinnest spot detected in said predetermined length of stock 120

for positioning said grading means with reference to the said thinnest spot, and means to maintain the leather piece stationary against lateral movement during said movement of the detecting mechanism, substantially as described.

5. In a machine of the kind described, edge-thickness detecting mechanism to detect thin spots at a plurality of points at 10 each of the edges of a died piece of stock, and including edge-detecting devices located and restricted to operate at said plurality of edge-spots, mechanism for maintaining the died piece stationary against lateral movement with relation to said devices while the latter are operating at said plurality of edge-spots thereof, grading means, and mechanism controllably related to all of the edge-detecting devices but selectively controlled by the one or ones thereof which 15 detects the thinnest of the plurality of said thin spots, for correspondingly adjusting said grading means, substantially as described.

25 6. In a machine of the kind described, detecting mechanism containing means responsive to the varying thicknesses throughout a considerable portion of the length of a leather piece, grading means for grading 30 said leather piece in accordance with the detecting mechanism, means operable by and controllably related to the entire responsive means but selectively controlled by that portion thereof which measures the thinnest 5 spot detected, for regulating said grading means with reference to said thinnest spot detected, and means for maintaining the leather piece immovable in an edgewise direction with relation to the engaging portion 10 of said detecting mechanism during the engagement thereof with the leather piece, substantially as described.

7. In a machine of the kind described, a plurality of at least three separated and independently operable feelers for engaging and detecting the varying thicknesses of a leather piece, grading means, and connections from said feelers to said grading means responsive only to that one of said plurality 50 of feelers which detects the thinnest of the corresponding plurality of spots so detected for setting said grading means in accordance with said thinnest detected spot, and means for operating said grading means as thus set, independent of said feelers and of movement of the leather piece, substantially as described.

8. In a machine of the kind described, a plurality of feelers for engaging and detecting the varying thicknesses of a leather piece, said feelers being located and movably operative at a corresponding plurality of spots in the leather piece while said leather piece is stationary against lateral 65 movement in the machine, a single grading

means common to all of said feelers, connections between said single common grading means and said feelers, and controllably related to all the feelers but selectively controlled by the one which detects the thinnest 70 spot among the plurality of spots detected by the said plurality of feelers, for setting said grading means in accordance with said thinnest detected spot, and means for so maintaining the leather piece stationary, 75 substantially as described.

9. In a machine of the kind described, a plurality of feelers for engaging and detecting the varying thicknesses of a leather piece, a single grading means common to all the feelers, means for maintaining the piece stationary against lateral movement with relation to the feelers while being engaged thereby, and connections from said feelers to said grading means operative while said 80 maintaining means is maintaining the leather piece thus stationary in the machine and controllably related to all the feelers but selectively controlled only by that individual feeler which detects the thinnest spot 85 among the plurality of spots detected by the said plurality of feelers, said connections including means for setting said grading means in accordance with said thinnest detected spot, substantially as described. 90

10. In a machine of the kind described, means to detect the thinnest spot of a plurality of spots detected in a considerable portion of the length of a leather piece, grading means for grading the said leather piece 100 when the latter is stationary in the machine in operative position with relation to the detecting means, means for so holding said piece stationary, means controllably related to all the detecting means but selectively 105 controlled by that portion thereof which detects the thinnest spot of said plurality of spots and arranged to operate prior to the grading operation of the grading means for setting said grading means with reference to said thinnest spot detected by said detecting means, and means independent of the detecting means to operate said grading means when thus set, to grade the leather piece, substantially as described. 110

11. In a machine of the kind described, grading means to grade shoe soles, taps, and the like, combined with means to detect the thinnest spot of a plurality of spots of different thicknesses in a predetermined area, said latter means including feeler mechanism operating by and having vertical engagement and pressure and movement only, simultaneously over all of said spots of said area, and means cooperating with said vertical feeler 125 mechanism for maintaining the leather piece held toward said feeler mechanism, and edgewise-immovable while being so engaged by the feeler mechanism, and connections from said detecting means for setting said 130

grading means to the thinnest measurement while the stock is still so engaged, substantially as described.

12. In a machine of the kind described, a device for indicating the grade of shoe soles, taps and the like, combined with a plurality of feelers for detecting a thin spot in the leather, means for maintaining the leather piece flat and held immovably against said feelers while being graded, connecting mechanism actuated by said detecting means to set said grading device, and locking means operating directly upon said grading device for positively locking said leather grading device and holding the same locked until the grading of the work has been accomplished substantially as described.

13. In a machine of the kind described, grading means for shoe soles, taps and the like, combined with movable feelers for detecting a thin spot in the leather, and mechanism coöperating with the leather and feelers for moving said feelers positively to final thinness-determining position, and for maintaining the leather flat and immovable edgewise with relation to the feelers while being graded and connecting mechanism actuated by said detecting means to set said grading means substantially as described.

14. In a machine of the kind described, grading means for shoe soles, taps and the like, combined with movable feelers for detecting a thin spot in the leather, means opposite said feelers for maintaining the leather flat and pressed toward the feelers, means for moving said pressing means, leather, and feelers together to thinness-determining position, and connecting mechanism controllably related to all the feelers but selectively controlled by the one nearest said pressing means for setting said grading means to indicate the thickness of the stock engaged by said one of the feelers, substantially as described.

15. In a machine of the kind described, grading means for shoe soles, taps, and the like, combined with leather-engaging detecting means, movable actuating mechanism for positively moving said detecting means to final leather-measuring position, and power-actuated means, for giving said actuating mechanism a positive predetermined movement to said final position, and connecting mechanism actuated by said detecting means to set said grading means in accordance with its leather-measuring position, substantially as described.

16. In a machine of the kind described, grading means for shoe soles, taps, and the like, combined with leather-engaging detecting means, actuating mechanism for said detecting means movable with the detecting means in one direction to final leather-measuring position, and power means for imparting a predetermined move-

ment to said actuating mechanism, the limit of such movement corresponding to said final leather-measuring position, and connecting mechanism actuated by said detecting means to set said grading means, substantially as described.

17. In a machine of the kind described, mechanism for engaging a leather piece on its opposite sides, including means for detecting the thinnest spot engaged, and adjustable piece-positioning controllers for engaging and positioning the leather piece at a plurality of points along its margin, substantially as described.

18. In a machine of the kind described, a series of three or more separately movable feelers for detecting variations in thickness of the stock felt of, combined with a plurality of stock-positioning controllers for directing and moving the stock to a predetermined position in the machine, and adjustable to accommodate different sizes of stock, and for governing the position of the stock with relation to the feelers, substantially as described.

19. In a machine of the kind described, a series of three or more separately movable feelers for detecting variations in thickness of the stock felt of, combined with a plurality of position controllers for directing and shifting the stock to a predetermined position in the machine and for governing the stock-positioning of the stock with relation to the feelers, said feelers and said controllers being adjustable to accommodate different sizes of stock, substantially as described.

20. In a machine of the kind described, a series of three or more separately movable feelers for detecting variations in thickness of the stock felt of, combined with a plurality of position controllers for governing the stock-positioning of the stock in the machine, said feelers and said controllers being also adjustable together to accommodate different sizes of stock, substantially as described.

21. In a machine of the kind described, a plurality of finger-like supports for the piece of stock to rest on at a corresponding plurality of places, pressure-applying means for gripping the stock thereon, and mechanism and connections coöperating with said means and supports for grading the stock according to its thickness at the thinnest one of the said plurality of places so gripped, substantially as described.

22. In a machine of the kind described, a plurality of finger-like supports for the piece of stock to rest on, at a corresponding plurality of places, pressure-applying means for gripping the stock thereon, position controllers for certain of said supports for engaging the leather piece along its margin, and mechanism and connections coöperating

- with said means and supports for grading the stock according to its thickness at the thinnest one of the said plurality of places so gripped, substantially as described.
23. In a machine of the kind described, a plurality of finger-like supports for the piece of stock to rest on, at a corresponding plurality of places adjustable toward and from each other to accommodate pieces of different sizes, pressure-applying means for gripping the stock thereon, and mechanism and connections coöperating with said means and supports for grading the stock according to its thickness at the thinnest one of the said plurality of places so gripped, substantially as described. 70
24. A machine of the kind described, having engaging means arranged in a curve to approximate the outline of a piece of stock to engage one side of said piece of stock, and adjusting means to move said engaging means to predetermined adjustments to accommodate pieces of different sizes, in combination with means coöperating with said first mentioned means to detect the thickness of the thinnest portion in a predetermined area of said piece, substantially as described. 75
25. A machine of the kind described, having a series of finger-like members arranged in a curve corresponding with the outline of a piece of stock to be graded, means coöperating therewith to grip the stock, and means for adjusting said members to form similar curves of different sizes, in combination with means coöperating with said members and gripping means to grade the stock according to the thickness of the thinnest portion of the piece so gripped, substantially as described. 80
26. In a machine of the kind described, grading means for shoe soles, taps, and the like, combined with leather-engaging detecting means to detect a thin spot in the leather, said latter means including mechanisms for engaging the opposite sides of the leather piece, position controllers for holding the leather piece in a predetermined edge-relation to the detecting means and invariably positioning successive leather pieces the same with relation to said mechanisms, and connecting mechanism actuated by said detecting means to set said grading means substantially as described. 85
27. In a machine of the kind described, grading means for shoe soles, taps and the like, combined with leather-engaging detecting means to detect a thin spot in the leather, said latter means including mechanisms for engaging the opposite sides of the leather piece, position controllers for invariably positioning successive leather pieces the same and holding said pieces stationary with relation to said mechanisms while being graded, the machine having an opening to permit the insertion of the leather piece between said mechanisms, and connecting mechanism actuated by said detecting means to set said grading means substantially as described. 90
28. In a machine of the kind described, leather-engaging detecting means to detect the thinnest spot in a predetermined area of the leather piece, means separate from said detecting means and independent in action of the leather piece for controlling and determining before the leather piece is inserted in the machine the definite position of the detecting means to grade the leather piece, with relation to the detecting means and the shape and extent of said area, coöperating means governed by the movement of said detecting means to grade the leather piece, and connecting mechanism controllably related to all of said detecting means but selectively controlled by that portion of the detecting means which engages the said thinnest spot to set said grading means, substantially as described. 95
29. In a machine of the kind described, grading means for shoe soles, taps, and the like, combined with leather-engaging detecting means, including a plurality of independent feelers arranged to approximate the contour of the died-out piece and arranged to engage simultaneously at a corresponding plurality of peripheral spots separated both widthwise and lengthwise of the sole and on the same side thereof, and connecting mechanism to set said grading means controllably related to all the feelers but selectively controlled by that feeler which detects the thinnest spot among said plurality of separated spots engaged by the feelers, substantially as described. 100
30. In a machine of the kind described, means for grading shoe soles, taps, and the like, combined with leather-engaging detecting means including a plurality of movable feelers at three or more places separated, from each other in the direction of the length and also of the width of the machine and having a detecting movement for detecting the thinnest spot of a corresponding plurality of spots in a predetermined area of the sole, and connecting mechanism from said detecting means to set said grading means in accordance with the thinnest of said plurality of spots detected, substantially as described. 105
31. In a machine of the kind described, means for grading shoe soles, taps, and the like, combined with leather-engaging detecting means including a plurality of independently movable feelers spaced apart from each other both widthwise and lengthwise of the machine and arranged to engage the leather simultaneously at a corresponding plurality of spots along each edge of the sole and having a detecting movement for detecting the 110
- 120
- 125
- 130

- thinnest spot of said plurality of spots, and connecting mechanism from said detecting means to set said grading means in accordance with the thinnest of said plurality of spots detected, substantially as described.
32. In a machine of the kind described, grading means for shoe soles, taps, and the like, combined with leather-engaging detecting means including a series of three or more mutually divergently movable feelers spaced apart from each other both widthwise and lengthwise of the machine and having a detecting movement for detecting the thinnest spot in a predetermined area of the sole, mechanism constructed and arranged to cause said feelers to engage the sole about its edges, and connecting mechanism to set said grading means in accordance with the thinnest of the plurality of spots detected, substantially as described.
33. In a machine of the kind described, grading means for shoe soles, taps, and the like, combined with leather-engaging detecting means, including a series of feelers to detect the thinnest spot in a predetermined area of the sole, said feelers being adjustable with relation to each other to positions separated both lengthwise and widthwise of the machine to fit different sizes of work, a pattern to so adjust said feelers, and connecting mechanism to set said grading means controllably related to all the feelers but selectively controlled by the one detecting the thinnest spot, substantially as described.
34. In a machine of the kind described, grade-marking means for shoe soles, taps, and the like, combined with leather-engaging detecting means to detect the thinnest spot of a plurality of spots of different thicknesses in a predetermined area of the work, connecting mechanism to set said marking means, means to lock said marking means, power-operated means acting independently of the setting mechanism for operating said locking means with reference to the marking means, said detecting means being constructed and arranged to receive and operate on the toe-end or fore-part of the work and said marking means being located to mark said toe-end while engaged by the detecting means, substantially as described.
35. In a machine of the kind described, grading means for shoe-soles, taps, and the like, combined with leather-engaging detecting means to detect the thinnest spot in a predetermined area, connecting mechanism to set said grading means, means to lock said grading means, and power-operated means acting independently of the setting mechanism for operating said locking means with reference to the grading means, said detecting means including mechanism constructed to maintain the heel end of the sole, at all times out of engagement with said grading means, substantially as described.
36. In a machine of the kind described, grading means for shoe soles, taps and the like, combined with leather-engaging detecting means including a pressure plate for engaging one side of the leather piece, feelers for engaging the opposite side of the leather piece, and means for positively moving both said pressure plate and also said feelers when so engaging a leather piece into leather-detecting position for detecting the thinnest spot engaged, and connecting mechanism controllably related to all the feelers but selectively controlled by the one nearest said plate to set said grading means, substantially as described. 70
37. In a machine of the kind described, grading means for shoe soles, taps and the like, combined with leather-engaging detecting means, including a pressure plate for engaging one side of the leather piece, feelers arranged to engage the opposite side of the leather piece adjacent its edge and means for positively moving said pressure plate and also said feelers when so engaging a leather piece into leather detecting position 75 for detecting the thinnest spot engaged, and connecting mechanism controllably related to all the feelers but selectively controlled by the one nearest said plate to set said grading means, substantially as described. 80
38. In a machine of the kind described, grading means for shoe soles, taps, and the like, combined with leather-engaging detecting means, including mechanisms for engaging the opposite sides of the leather piece, 85 said machine having an inlet and outlet for the leather piece at one side of the machine only and means for preventing the escape of the leather piece excepting at said outlet, connecting mechanism actuated by said detecting means to set said grading means, and power operating mechanism for actuating said detecting means, said power operating mechanism being constructed and arranged to operate said detecting means during short 90 intervals between relatively long intervals of inaction, substantially as described. 95
39. In a machine of the kind described, a plurality of feelers spaced apart both widthwise and lengthwise of the machine, means 100 for maintaining said feelers at all times in vertical position, said feelers being relatively movable laterally into position to operate on the side of a leather piece adjacent its edge, means normally maintaining the ends of said 105 feelers yieldingly in the same horizontal plane when not feeling, transmitting mechanism responsive to the thinness-detecting movements of at least one of said feelers, grading means controlled by said transmitting mechanism, and means for pressing the leather piece against the ends of said feelers, substantially as described. 115
40. In a machine of the kind described, detecting mechanism, including a plurality 120

of feelers having a detecting movement in a direction toward the leather piece, and at least some of the feelers having also an independent movement with relation to each other to positions varying in the direction of the length and also in the direction of the width of the machine, position controllers adjacent said feelers for controlling the position of the leather piece with relation to said feelers, grade indicating means, and transmitting mechanism from said feelers to the indicating means for actuating the latter, substantially as described.

41. In a machine of the kind described, 15 detecting mechanism, including a plurality of feelers having a detecting movement in a direction toward the leather piece and also having a lateral movement with relation to each other for positioning them to operate 20 on the edges of said leather piece, position controllers capable of controlling the position of the leather piece in the machine and with relation to the feelers, grade indicating means, and transmitting mechanism connected to the feelers for controlling the indicating means in accordance with the detecting movement of at least one of the feelers, substantially as described.

42. In a machine of the kind described, 30 a plurality of feelers, means for maintaining said feelers at all times in vertical position, said feelers having movement independently laterally for positioning them to operate on the edges of a leather piece, position controllers adjacent said feelers for controlling the position of the leather piece, means normally maintaining the feeling surfaces of said feelers yieldingly in the same horizontal plane, when inactive, grading means, 40 transmitting mechanism for adjusting the grading means in accordance with the movements of at least one of said feelers, and means for pressing the leather piece against the ends of said feelers, substantially as described.

43. In a machine of the kind described, 45 a plate, mechanism to detect the thinnest spot of a plurality of thin spots of a prescribed area, including a plurality of feeler pins vertically mounted yieldingly in said plate to receive a piece of leather on their upper ends, and a pressure plate above said feelers for pressing the leather hard down upon the yielding feeler pins, grading means, and connecting actuating mechanism between said grading means and said feeler pins responsive to the pin which detects the thinnest spot for transmitting to the grading means the detecting movement of the said 55 pin substantially as described.

44. In a machine of the kind described, 60 means for detecting a thin spot in a leather piece, a grade marker, connecting means controlled by said detecting means for setting said grade marker, a locking device for

directly locking said grade marker when set, means for releasing the locking device, a slide for supporting and operating said marker, and means for moving said slide and marker positively into marking position 70 substantially as described.

45. In a machine of the kind described, 75 means for detecting a thin spot in a leather piece, a grade marker, connecting means controlled by said detecting means for setting said grade marker, a locking device for directly locking said grade marker when set, means for releasing the locking device, a slide for supporting and operating said marker, and means for moving said slide 80 and marker positively into marking position on the leather piece while engaged by said detecting means substantially as described.

46. In a machine of the kind described, 85 means for detecting a thin spot in a leather piece, a grade marker, connecting means controlled by said detecting means for setting said grade marker, a slide for supporting and operating said marker, and a sliding carrier for supporting said slide and provided with means for engaging and holding the leather piece substantially as described.

47. In a machine of the kind described, 90 carrier plates separated to form a pocket adapted to receive a pattern for predetermining the area and contour to be felt of, and provided with divergent slots opening into said pocket, detecting mechanism including feeler pins movably mounted in said slots to feel of and determine thin spots in a leather piece, grade indicating means, 95 means to move the pins for their feeling operation, and connecting mechanism controlled by said feeler pins for setting said grade indicating means substantially as described.

48. In a machine of the kind described, 100 carrier plates separated to form a pocket adapted to receive a pattern for predetermining the area and contour to be felt of, 105 said plates having divergent slots opening into said pocket, feeler pins movably mounted in said slots to feel of and determine thin spots in a leather piece, means to so move the pins, grade indicating means, a slotted head engaged by said feeler pins, said pins being movable independently of said head 110 when engaged by thick spots of the leather piece, and controlling the position of said head when engaging a thin spot of the leather piece, and connecting means from said head to said grade indicating means 115 for setting the latter in accordance with said controlled position of said head substantially as described.

49. A machine of the class described, having, in combination, a plurality of detectors 120 independently movable in gripping relation 125

- to the work, a relatively rigid device extending opposite to all of said detectors and adapted to engage over one flat side of a leather piece to coöperate with said detectors to grip the work between said device and the detectors, means for providing a relative movement toward each other of said detectors and gripping device, whereby the stock is engaged thereby on its opposite flat sides, and selective means controlled by at least one of the detectors for selecting and indicating the thickness of the thinnest portion of the stock engaged by the detectors.
50. A machine of the class described, having, in combination, means to engage a piece of stock on one flat side and to contribute to maintain the same flat when the stock is hard pressed thereby, a plurality of detectors spaced apart to engage the stock adjacent its edges on the other flat side, means for relatively moving said detectors and said engaging means directly toward each other in gripping relation to the stock sufficient for the detecting operation, and selective means controlled by at least one of the said detectors for indicating solely the thickness of the thinnest portion of the stock engaged by the detectors.
51. A machine of the class described, having, in combination, means against which a piece of stock may be gripped, detecting means comprising a plurality of detectors independently movable in the direction of said means, an actuator for causing one of said means to approach the other whereby the stock is gripped therebetween, means for moving said actuator, and means controllably related to all the detectors but selectively controlled by the one or ones nearest said first named means and including a single common member actuated to indicate the thickness of the stock engaged by such one or ones of the detectors.
52. A machine of the class described, having, in combination, means against which a piece of stock may be gripped, a plurality of detectors movable in the direction of said means either collectively or independently, means for producing relative movement between said detectors and said first named means to grip the stock between them in a plurality of places, and means controllably related to all the detectors but selectively controlled by the one or ones nearest said first named means and including a single common member actuated to indicate the thickness of the stock engaged by such one or ones of the detectors.
53. A machine of the class described, having, in combination, a substantially rigid plate against which a piece of stock may be gripped flatwise, detecting means, comprising a plurality of detectors located opposite and in line with said plate and independently movable in the direction of said plate, an actuator for moving said plate toward said detectors to grip the stock forcibly flatwise against the detectors, and means controlled by the detecting means for indicating the thickness of the thinnest portion of the stock engaged by the detectors.
54. A machine of the class described, having, in combination, a vertically movable device against which a piece of stock may be gripped flatwise, a plurality of detectors movable within the area of said device in the direction of said device either collectively or independently, means for positively moving said device toward said detectors to grip the stock against the latter in a plurality of places, and selective means capable of responding to any one of the detectors, according as the thickness of different pieces of stock may require and always controlled by that one detector which is permitted by any given piece of stock to come nearest to said device for indicating the distance between the two.
55. A machine of the kind described, having, in combination, engaging means for engaging one side of a piece of stock, means for gripping said piece against said engaging means and for holding it in such position, and selective means for selecting and indicating solely the thinnest portion so gripped, substantially as described.
56. A machine of the kind described, having, in combination, means against which a piece of stock may be pressed, yielding mechanism coöperating with said means to press said piece against said means and to grip it in such position, actuating means for giving said pressing mechanism a gripping hold on the piece, and selective means for determining the thinnest portion so pressed and grading the stock according to said thinnest portion, substantially as described.
57. A machine of the kind described, having, in combination, means for engaging a piece of stock in at least three divergently separated places approximately simultaneously, actuating mechanism for said engaging means, and selective means for selecting and visibly indicating the thickness of the stock at the thinnest place of said at least three divergently separated places so engaged simultaneously, substantially as described.
58. A machine of the kind described, having, in combination, means for yieldingly engaging a piece of stock in at least three divergently separated places approximately simultaneously, actuating mechanism for said yielding engaging means, and selective means for detecting and visibly indicating the thickness of the stock at the thinnest of the three or more places thus simultaneously engaged, substantially as described.
59. A machine of the kind described, having, in combination, engaging means for en-

gaging on side of the stock, a plurality of relatively movable detectors to engage the opposite side of the stock, an actuator for causing said engaging means and detectors to approach each other and to grip the stock between them, means for moving said actuator in a fixed path, and selective means controllably related to all the detectors but selectively controlled by the detector nearest to said engaging means for grading the stock according to the thickness of the thinnest portion of the stock engaged by the detectors substantially as described.

60. A machine of the kind described, having, in combination, engaging means for engaging one side of a piece of stock, a plurality of relatively movable detectors for engaging the other side of said piece of stock, means for producing relative movement between said detectors and engaging means to grip the stock in a plurality of places, so as to hold it stationary while being detected, means for classifying the stock as to thickness, means for controlling said classifying means, and means including said detectors for setting said controlling means in accordance with the thinnest portion of the stock so gripped, substantially as described.

61. A machine of the kind described, having, in combination, engaging means for engaging one side of the stock, a plurality of relatively movable detectors, means for producing relative movement between said detectors and engaging means to grip and hold stationary the stock in a plurality of places, and means for visibly indicating the shortest distance between the engaging means and that detector which is nearest to the latter, substantially as described.

62. A machine of the kind described, having, in combination, engaging means for engaging one side of the stock, a plurality of detectors, means including springs permitting said detectors to yield, means for causing relative movement between said detectors and engaging means to grip the stock, and means controllably related to all the detectors but selectively controlled by the one nearest said engaging means for grading the stock according to the thickness of the thinnest portion of the stock so gripped, substantially as described.

63. A machine of the kind described, having, in combination, engaging means for engaging one side of a piece of stock, a plurality of detectors for engaging the opposite side of the piece of stock, means including a separate spring for each detector for permitting said detectors to yield, means for causing said stock to be gripped and held between said engaging means and detectors, and means controllably related to all the detectors but selectively controlled by the one nearest said engaging means for grading the stock according to the thickness of

the thinnest portion of the stock so gripped, substantially as described.

64. A machine of the kind described, having, in combination, engaging means for engaging one side of a piece of stock, a plurality of detectors, means for causing said stock to be gripped and held stationary against lateral movement between said detectors and engaging means with an increasing pressure, and means controllably related to all the detectors but selectively controlled by the one nearest said engaging means for grading the stock according to the thickness of the thinnest portion so gripped, substantially as described.

65. A machine of the kind described, having, in combination, means for engaging a sole simultaneously at a series of separated spots throughout a predetermined extent of the margin thereof and for holding said sole from movement, a grading controller, and automatic means including said engaging means for setting said controller in accordance with the thinnest spot of said series so simultaneously engaged, substantially as described.

66. A machine of the kind described, having, in combination, engaging means for engaging one side of a piece of stock, a plurality of relatively movable detectors, means for holding said engaging means and detectors from movement across said piece as well as from movement longitudinally thereof during the operation upon said piece of stock, means for causing relative movement between said engaging means and detectors in a direction approximately perpendicular to the plane of said piece whereby said piece is engaged in several places, and means controllably related to all the detectors but selectively controlled by the one nearest said engaging means for grading said piece according to the thickness of the thinnest place so engaged, substantially as described.

67. A machine of the kind described, having, in combination, engaging means for engaging one side of a piece of stock, and holding said stock stationary with relation to the detectors while being graded, a plurality of relatively movable detectors, means for moving said detectors into gripping contact with said stock and for holding them in such position, and means responsive to that detector which is nearest the said engaging means for grading the stock according to the thinnest portion engaged by said detectors, substantially as described.

68. In a machine for detecting the thinnest place in a given area of a piece of stock of varying thickness, engaging means for engaging one side of said piece of stock, a series of detectors, a spring for each detector tending to move its detector toward said engaging means in opposition to an actuator, combined with said actuator to oppose

said spring tendency and to effect a pressing of the stock between said engaging means and the detectors, means to move said actuator toward the stock whereby the latter is 5 pressed on one side by said engaging means and on the other side yieldingly by said detectors, and means controllably related to all the detectors but selectively controlled by the one nearest said engaging means for 10 grading the stock substantially as described.

69. In a machine of the kind described, a plurality of detectors individually movable to variations in the thinness of the leather, means opposed to the detectors and between 15 which and said detectors the leather may be held or pressed, coöperating mechanism for raising and lowering said detectors, and grading means coöperating with said detectors for grading the leather piece according 20 to the thinnest point so pressed in the leather piece, substantially as described.

70. In a grading machine for leather soles and died out pieces of leather, the combination with engaging means for engaging one side of a died out piece, of a plurality of detectors arranged approximately perpendicular to said engaging means and disposed in a curve similar to the outline of the died out piece, operating 30 means to grip said engaging means and detectors against the leather piece, means to individually accommodate said detectors to variations in the thinness of the leather piece, and means coöperating with said detectors for grading the leather piece according 35 to the thinnest point detected in the edge of the leather piece, substantially as described.

71. A machine of the kind described, having, in combination, means against which a piece of stock may be gripped, detecting means comprising a plurality of detectors independently movable in the direction of said means, an actuator for causing one of 45 said means to approach the other whereby the stock is gripped therebetween, means for moving said actuator, and means controllably related to all of said detectors but selectively controlled by the one which is 50 nearest to said first mentioned means for grading the stock according to the thickness of the thinnest portion of the stock engaged by the detectors, substantially as described.

72. A machine of the kind described, having, in combination, means against which a piece of stock may be gripped, a plurality of detectors movable in the direction of said means either collectively or independently, means for producing relative movement between said first mentioned means and said detectors to grip the stock in a plurality of places, and means controlled by that detector which is nearest to said first

named means for grading the stock according to the distance between the two, substantially as described.

73. A machine of the kind described, having, in combination, means against which a piece of stock may be pressed, a plurality of detectors, means, including springs, permitting said detectors to yield, for causing relative movement between the various detectors and to coöperate with said first mentioned means in gripping the stock between the detectors and said first mentioned means, and means controllably related to all the detectors but selectively controlled by the one or ones nearest said first named means and including a single common member actuated to grade the stock according to the thickness of the stock engaged by such one or ones of the detectors, substantially as described.

74. A machine of the kind described, having, in combination, engaging means for engaging one side of a piece of stock, a plurality of independently movable detectors for engaging the opposite side of the stock, means for permitting all of said detectors to engage said stock and for maintaining them in gripping engagement therewith, and means controllably related to all the detectors but selectively controlled by the one or ones nearest said first named means and including a single common member actuated to grade the stock according to the thickness of the stock engaged by such one or ones of the detectors, substantially as described.

75. In a machine of the kind described, means adapted to engage the stock over an extended area for flattening out the wrinkles and bends both lengthwise and widthwise in said area, including a series of post-like detectors to engage one side of the stock at a plurality of places separated from each other both lengthwise and widthwise over said area and mechanism acting in opposition to said flattening means to engage the other side of the stock, combined with means controllably related to all the detectors but selectively controlled by the one or ones nearest said engaging mechanism to grade the stock according to the thickness of the stock engaged by such one or ones of the detectors, substantially as described.

76. A machine of the kind described, comprising engaging means for engaging one side of a leather piece, a plurality of vertically movable detectors for engaging the opposite side of the leather piece and disposed in a curve approximately similar to the shape of the adjacent portion of the leather piece, yielding means for maintaining said detectors in engagement with the leather piece, a vertically movable horizontal member in position to be actuated

by any one of said detectors, supporting and guiding means for said member mounted to restrict said member to vertical movement, means normally tending to move said member in opposition to said detectors, and means actuated by said member and thereby controllably related to all the detectors but selectively controlled by the one or ones nearest said first named means for graduated

10 ing the stock according to the thickness of

the stock engaged by such one or ones of the detectors, substantially as described.

In testimony whereof, I have signed my name to this specification, in the presence of two subscribing witnesses.

ELMER P. NICHOLS.

Witnesses:

GEO. H. MAXWELL,
Wm. J. PIKE.

It is hereby certified that in Letters Patent No. 1,113,472, granted October 13, 1914, upon the application of Elmer P. Nichols, of Manchester, New Hampshire, for an improvement in "Leather-Grading Machines," errors appear in the printed specification requiring correction as follows: Page 6, lines 95 and 107, for the word "position" read *stock-positioning*; same page, lines 98 and 108, for the compound word "stock-positioning" read *position*; same page, line 109, after the word "being" insert the word *both*; page 12, line 103, after the word "area", insert the words *both lengthwise and widthwise*; same page, line 104, strike out the words "both lengthwise and widthwise"; and that the said Letters Patent should be read with these corrections therein that the same may conform to the record of the case in the Patent Office.

Signed and sealed this 10th day of November, A. D., 1914.

[SEAL.]

R. F. WHITEHEAD,
Acting Commissioner of Patents.
